HERMETICALLY SEALED CRYSTAL

Philip R. Hoffman, Carlisle, Pa., assignor to
 Reeves-Hoffman Corporation, Carlisle, Pa., a
 corporation of Pennsylvania

Application January 23, 1948, Serial No. 3,939

5 Claims. (Cl. 171—327)

1

This invention relates to improvements in hermetically sealed electrical units and relates more particularly to an hermetically sealed crystal of the fixed frequency type.

The various objects and advantages of the invention will be apparent and best understood from the following description and the accompanying drawings in which:

Fig. 1 is a side view in vertical section of a container embodying the invention;

Fig. 2 is a section view taken along the line 2—2 of Fig. 1;

Fig. 3 is a top view of the container illustrated in Fig. 1; and

Fig. 4 is a side view in section of a closure member for the container illustrated in Fig. 1.

The importance of hermetically sealing electrical units so that the electrical elements will be protected from changes in atmospheric conditions, such as moisture, that will affect their electrical characteristics and proper performance is well known. One method of constructing an hermetically sealed container is illustrated in Patent No. 2,057,790. In such a construction the end closure pieces for the container have a resilient material such as rubber on their outer surfaces and the ends of the container are crimped or spun over so that the turned-in end of the container presses into the resilient material to form the seal. In this type of construction the entire periphery of the end of the container must be brought into engagement with the resilient material in order to form an effective seal. This makes it necessary to have special jigs or spinning tools to perform this operation and generally limits the shape of the container that may be used to a cylindrical container because of the nature of the closure operations required. In addition, such an operation must be carefully performed since even the smallest opening between the end of the container and the resilient material will destroy the effectiveness of the seal.

An hermetic seal may be obtained in accordance with the present invention with practically any shape of container and the closure may be effectively made on an ordinary press. The necessity for bringing the entire edge of the container into contact with the outer surface of the end closure is eliminated and pressure on the end closure at a few spaced points will insure a proper seal.

In a container embodying the present invention, as illustrated, there is a container 10 made of a suitable material such as brass, aluminum, or the like. The container 10 illustrated is oval in shape and is closed at one end. The container is

2

open at its other end so that a crystal 11 may be placed inside of the container. The crystal 11 is of the fixed frequency type and is supported by wire clips 12 and 13 that are in turn supported from the end closure 14.

The ends of the wire clips 12 and 13 holding the crystal 11 contact conductors 15 and 16 respectively that extend along opposite sides of the crystal 11. The other ends of the wire clips 12 and 13 are soldered to eyelets or rivets 17 and 18, respectively. The eyelets 17 and 18 extend through the end closure 14 and serve as wiring terminals to which lead wires 19 and 20 may be affixed.

15 The end closure 14 is laminated and has a rigid insulating material 21 such as a molded synthetic resin, or the like on one side and a resilient insulating material 22 such as a synthetic rubber or the chlorobutadiene polymer type or the like on its other side.

10 The open end of the container is somewhat enlarged to accommodate the laminated end closure. The end closure 14 is fitted into the container with the resilient material 22 resting on 25 a lip 23 formed by a downwardly and outwardly sloping shoulder 23a. The lip 23 extends around the inside of the container and supports the end closure inside of the container. When the end closure has been placed in the container, the end 30 of the container is crimped or pressed over the edges of the end closure to hold the end closure in the container. The turned over edges of the container engage with and press against the rigid outer surface of the end closure. This forces 35 the resilient material 22 into contact with the entire periphery of the lip 23 and also with the inclined shoulder 23a hermetically sealing the container.

40 The hermetic seal obtained in this manner is not affected if the end of the container does not engage the end closure around its complete perimeter. In fact it is sufficient if the end of the container engages with the end closure 14 at a few spaced points as this will force the resilient material 22 into engagement with the lip 23 and the shoulder 23a at all points. Thus, by this arrangement an effective seal may be obtained regardless of slight irregularities or variations in the manner that the end of the container engages 45 with the end closure.

50 When the end closure is secured in place, the resilient material 22 flows along the inclined shoulders 23a as indicated at 24. This flowing of the resilient material not only forms a highly effective hermetic seal, but is also provides a grip-

ping action that prevents breaking of the seal by shrinkage or sagging of the end closure. The eyelets 17 and 18 forming the terminals for the electrical connections are also pressed into the resilient material so that they are effectively sealed against leakage of moisture or air.

An hermetically sealed container made in accordance with the present invention not only may be made in any shape desired, but it is also extremely economical to manufacture as the unit may be assembled without special jigs or tools.

It will be apparent that such a container may be used for any type of electrical unit desired and it will be understood that various changes may be made in the embodiment of the invention that has been illustrated and described without departing from the scope of the invention as defined by the appended claims.

I claim:

1. In an hermetically sealed electrical unit the combination of a container, said container having an opening at one end thereof, an inclined internal shoulder extending around the inside of the container and an end closure of insulating material fitted into said container and being supported on a lip formed by the inclined shoulder, said end closure having a resilient material on its inner surface and a rigid material on its outer surface and the edges at the end of the container being turned over the edge of the end closure to hold the closure in place and the resilient material in engagement with the internal lip and shoulder.

2. An hermetically sealed electrical unit as defined in claim 1 wherein the end closure serves as a support for an electrical element enclosed in the container and wiring terminals extend through the end closure.

3. An hermetically sealed electrical unit as defined in claim 1 wherein the resilient material on the end closure is synthetic rubber like material.

4. An hermetically sealed crystal of the fixed frequency type comprising a container, said container having an opening at one end thereof, an

inclined internal shoulder extending around the inside of the container, an end closure of insulating material fitted into the container and resting on a lip formed by said inclined shoulder, said end closure having an inner surface of resilient material engaging with said lip and an outer surface of rigid material, the edges of the end of the container being turned in and engaging with the outer surface of the end closure, terminals extending through the end closure and a crystal of the fixed frequency type connected to and supported from said terminals.

5. In a hermetically sealed electrical unit the combination of a container, said container having an opening at one end thereof, an internal shoulder extending around the inside of the container at its open end with said shoulder being spaced from the end of the container, an end closure of insulating material fitted into the open end of said container and resting on said shoulder, said end closure consisting of an outer member of rigid material and an inner member of resilient material, inwardly extending portions carried by said container at its open end, said inwardly extending portions extending over and engaging with the rigid outer member of the end closure and urging the resilient inner member of the end closure into sealing engagement with the internal shoulder of the container and an electrical terminal extending through said end closure, said electrical terminal having a flanged portion in sealing engagement with the resilient inner member of the end closure.
